United States Patent Office.

CHRISTIAN HENRY KOCK, OF DAVENPORT, IOWA.

Letters Patent No. 91,943, dated June 29, 1869.

IMPROVEMENT IN WATER-ELEVATORS.

The Schedule referred to in these Letters Patent and making part of the same.

To all whom it may concern:

Be it known that I, CHRISTIAN HENRY KOCK, of Davenport, in the county of Scott, and State of Iowa, have invented a new and improved Method of Raising Water; and I do hereby declare that the following is a full, clear, and exact description thereof, which will enable others skilled in the art to make and use the same, reference being had to the accompanying drawings, forming part of this specification.

This invention relates to a new arrangement for elevating water from wells and cisterns; and consists in confining a number of spiral springs in a suitable cylinder, and compressing them by a windlass, by which compression (in combination with a piston) a vacuum is formed, and water admitted, while, by the recoil of the springs, the water is forced from the cylinder, through a pipe or pipes, to any point where it may be required for use.

In the accompanying sheet of drawings—

Figure 1 represents a sectional elevation of my arrangement.

Similar letters of reference indicate corresponding parts.

A is a cylinder, of any desired length and diameter, placed in an upright position, as seen in the drawing.

B represents spiral springs (more or less in number) separated by loose disks, C.

D is a piston, which works water-tight in the cylinder A.

E is a ball-valve, which closes when the piston descends, the seat being at F; and g being the basket by which the ball is supported.

H is the metallic ribbon by which the piston is raised and the springs compressed.

The ribbon is attached to the piston, and to a windlass, I, around the drum of which it is wound by means of the gear-wheels J and crank K, as seen in the drawings.

As the piston is raised, a vacuum is formed in the cylinder A, and the water rushes up through the supply-pipe L, to fill it.

The water which passes into the cylinder from the pipe L, reaches the space beneath the piston, and fills the cylinder.

M is a ball-valve at the lower end of the pipe L. This valve closes the pipe when the flow of water through it ceases.

The valve E will always be closed when the piston is pressed upon the water beneath, or except when being raised.

N is the discharge-pipe.

For the perfect working of the machine, it is necessary that the cylinder be full on the start, and to insure this, there is a pipe, O, on top of the cylinder, through which water may be introduced.

The water may be discharged from the spout p, or be conveyed off laterally, to any desired point, or be discharged at a more elevated point, as may be desired.

It will be seen that the distance to which the water may be elevated will depend upon the power of the springs B.

The cylinder may be made to contain a large quantity of water, so that by spending a few moments in raising the piston, the water will continue to flow for a whole day, as it may be required for family use.

A hose-pipe may be attached to the spout p, and the water, under the powerful head thus obtained, may be discharged for the extinguishment of fires.

The machine may also be used to good advantage in elevating water at railroad stations, and for various other purposes.

The metallic ribbon H is tightly packed at the top of the cylinder, between two elastic rollers, as seen at Q, so that air may not enter the cylinder.

The springs B are formed so that they fold together, and take up but slight space in the cylinder when compressed. The disks C move up and down with the springs.

Having thus described my invention,

I claim as new, and desire to secure by Letters Patent—

The combination of the cylinder A, spiral springs B, separated by the loose disks C, the piston D, ball-valve E, and its seat F, the metallic ribbon H, the windlass, the supply-pipe L, having the ball-valve m, and the discharge-pipe N, all arranged and operating as described, for the purpose specified.

The above specification of my invention signed by me, this 25th day of January, 1869.

CHRISTIAN HENRY KOCK.
